UNITED STATES PATENT OFFICE.

GERSHOM M. PETERS, OF CINCINNATI, OHIO, ASSIGNOR TO THE PETERS CARTRIDGE COMPANY, OF CINCINNATI, OHIO, A CORPORATION OF OHIO.

SHELL.

No. 905,358.

Specification of Letters Patent.

Patented Dec. 1, 1908.

Application filed November 23, 1906. Serial No. 344,686.

To all whom it may concern:

Be it known that I, GERSHOM M. PETERS, a citizen of the United States, residing at Cincinnati, in the county of Hamilton and 5 State of Ohio, have invented certain new and useful Improvements in Shells, of which the following is a full, clear, and exact specification.

The invention relates to improvements in 10 the construction of shells for use in firing powders and has been found particularly applicable to shotgun shells using nitro powders. In order to get the best effects from these powders, an extra strong primer 15 is required of a peculiar type. The primer cup must be of a length sufficient to contain an extra amount of fulminate and an anvil capable of resisting the blow of the plunger or primer pin and the force of the explosion. 20 The whole primer must be of sufficient length to pass through the extra, reinforced paper base, so as to introduce the flame directly into the midst of the powder. These requirements necessitate a primer quite differ- 25 ent in form from that in common use for black powders, viz., a long cup and a long flat anvil cut away at the bottom to avoid resistance to the flame. This cup containing the fulminate and the anvil, is placed inside 30 an exterior cup having a flange at the outer end, to keep it suspended in the base, with a closed bottom, (except as to a small opening through which passes the flame) on which bottom rests the legs of the anvil for sup- 35 port, as well as the primer cup itself. The whole is then thrust firmly and tightly into and through a central opening in the base of the shell, a depression being made in the exterior of the butt or base to let in the flange 40 of the outer cup. This primer is called a "battery cup primer" and is in constant use among the manufacturers of nitro shells for shotguns and is sufficient for all ordinary purposes. But with an extra strong powder, 45 or an extra heavy charge, or because of defects in construction, this primer is not always satisfactory, and sometimes causes serious accident or injury to the man back of the gun. The primer not infrequently is loos- 50 ened by the force of the explosion of the powder and driven back and gas escapes around the outer cup. Sometimes, also, the

center of the primer cup is pierced by the force of the plunger together with the internal force coming back against it, and gas 55 escapes at that point, thus greatly endangering the eye of the shooter.

The object of the present invention is to avoid these difficulties and to that end to so fasten the battery cup primer in the base 60 of a shell, as that it cannot become loosened and driven back, and to so protect the primer cup as to avoid piercing. No change whatever is made in the construction of the ordinary battery cup primer, except perhaps to 65 slightly diminish the thickness of metal in the cup containing the fulminate. But with the present invention, there is provided a hood or a third cup to inclose the battery cup primer, which is flanged or flared into 70 a rim on the outer end to correspond to the flange or flare of the battery cup for the purpose of supporting it in position, and is sufficiently long to be brought through the base of the shell and to be upset and firmly 75 embedded in such base on the inside.

Like reference letters designate similar parts in the several figures of the drawing, in which:—

Figure 1 is an enlarged longitudinal sec- 80 tional view of the shell, having the end of such shell opposite the breech or base broken away. Fig. 2 is a cross sectional view on the line 2—2, Fig. 1. Fig. 3 is an enlarged detail view in longitudinal section of the 85 primer hood or cover in the form in which it incloses the battery cup primer. Figs. 4, 5 and 6 are enlarged detail views of parts of the primer, respectively termed "battery cup", "primer cup" or "fulminate cup" 90 and "anvil".

The particular invention may be employed with different forms of shells and shells having different kinds and different charges of powder, but there is illustrated in the drawings and will now be described a form of shell used in connection with a kind of powder to which the invention is particularly applicable and found in practice most ad- 95 vantageous.

Referring to the drawings to aid this description, 1 designates a metal cup or butt, 2 the paper shell, and 3 the interior paper base, which are all of the ordinary forms for nitro

powder and are of the central fire type with a hole through the center of cup 1 and base 3 for the insertion of the primer.

4 is the ordinary cup usually designated 5 as the "battery cup", having a vent as at 4^a and flange 4^b.

6 is the interior cup, usually called the "primer cup", which contains the fulminate 5, and the anvil 7, the latter of the ordinary 10 long, flat type. The primer cup with fulminate end outward, is then forced into the battery cup with the edges of the primer cup and legs of the anvil firmly resting on the bottom. The battery cup primer as a whole, 15 is now placed inside a third, and exterior, cup or hood 8, which, in this stage of the operation of assembling, is a thin metallic shell with straight sides, having an internal diameter in excess of the external diameter 20 of the flange 4^b of the battery cup and extending beyond its length. Then, by any suitable method or device, the shell or hood 8 is compressed about the flange 4^b and tightened about the sides of the battery cup 25 4. By another operation, it is forced as a whole through the opening in cup 1 and base 3, the flange of the hood, as 8^b, resting within the depression provided for it in the exterior surface of the base and upon the 30 flange of such base there formed. By the same operation, the inner edges 8^a of the hood 8 extending through and beyond the base 3, are turned back, upset or outwardly crimped as at 8^a, and embedded in the paper 35 base or in the particular form of shell shown in what is ordinarily known as the wound wad as at 3^a; all of which may be more definitely understood by reference to the parts illustrated in the figures of the drawing.

40 It will thus be seen that the fulminate has over it a double covering of metal, which will prevent piercing at that point, and that a gas-tight union is formed between the battery cup primer and the base of the shell, 45 and the primer secured in position so that it cannot get loose nor have any opening around the sides. There has now been described a specific embodiment of the invention such as is shown in the drawings, which 50 has been found advantageous in practice, but it is to be understood that the details might be readily varied by a person skilled in the art without departing from the spirit of the invention, and the use of the invention 55 while particularly desirable in connection with central fire shotgun shells employing nitro powder, is not to be understood as limited thereto.

What I claim and desire to secure by Letters Patent is:

1. In a shell, a battery cup primer comprising a fulminate or primer cup and an inclosing battery cup, an additional cup or hood inclosing the battery cup primer and

inserted with it through the base of the 65 shell and secured in position.

2. In a shell having an aperture through its base, a battery cup primer comprising a fulminate or primer cup and an inclosing battery cup being placed in said aperture, 70 and an imperforate hood also placed within said aperture and inclosing the sides and outer end of said primer and secured to the base of the shell.

3. In a shell having the usual battery cup 75 primer provided with a flange and sides, a ductile metallic covering or hood inclosing the flange and sides of said primer and being firmly secured at both its internal and external extremities to the base of the shell. 80

4. In a shell having a base provided with an opening through it and a hooded battery cup primer comprising a fulminate or primer cup and an inclosing battery cup being placed in such opening and a flange in 85 said base about said opening, depressed to receive the body and flange of said hooded battery cup primer.

5. In a shell having a base with an aperture through it, a battery cup primer comprising a fulminate or primer cup, a battery cup, and an inclosing hood with such hood placed in the aperture of the base and having one of its edges reamed outward, turned back and firmly compressed in the paper 95 base.

6. In a shell having a base provided with a reinforcing wound wad with an aperture through it, and a hooded battery cup primer, the hood of which passes through such wad 100 and has one of its edges firmly upset into such wad.

7. In a shotgun shell for nitro powders, having a battery cup primer comprising a fulminate or primer cup and an inclosing 105 battery cup, a secondary exterior covering or hood for strengthening and protecting the base of the primer cup containing the fulminate.

8. In a shotgun shell for nitro powders, 110 the combination with an exterior base containing an interior reinforcing wound wad having an opening therethrough and a hooded battery cup primer placed in such opening and secured firmly to said base and 115 to said wad.

9. In a shotgun shell, including a paper tube and a cup of ductile material, and an interior wad or reinforcement having an opening therethrough in combination with 120 a battery cup primer and an inclosing hood imperforate at one end and having its other end crimped into gas-tight connection with the wad.

10. In a central fire shotgun shell for nitro 125 powders, the combination with a paper tube joined to a base of ductile material perforated at its center, having the edges sur-

rounding such perforation depressed, in combination with a primer and a flaring hood inclosing the outer end and sides of such primer, and itself supported on the depressed edge surrounding the perforated center of the base and having its other end crimped or upset into gas-tight connection with the wound or reinforcing wad.

In testimony whereof I have signed my name to this specification, in the presence of ¹⁰ two subscribing witnesses, on this 2d day of November A. D. 1906.
